UNITED STATES PATENT OFFICE.

WILLIAM G. WOOD, OF BERKELEY, CALIFORNIA, ASSIGNEE TO BERKELEY LIGHT CORPORATION, OF SAN FRANCISCO, CALIFORNIA, A CORPORATION OF NEVADA.

HEADLIGHT.

1,363,073.

Specification of Letters Patent. Patented Dec. 21, 1920.

Application filed August 15, 1918. Serial No. 249,888.

To all whom it may concern:

Be it known that I, WILLIAM G. WOOD, a citizen of the United States, residing at Berkeley, in the county of Alameda and 5 State of California, have invented new and useful Improvements in Headlights, of which the following is a specification.

This invention relates to headlights such as are employed on automobiles, locomotives 10 and the like, and particularly to improvements on the structure shown in my co-pending application entitled, "Headlight," filed August 5, 1918, Serial No. 248,303.

In the present invention, I provide a lamp 15 which, following generally the principles of the lamps disclosed in the above mentioned application, employs a reduced light emitting aperture through which a cone-shaped beam of sharp outline is projected. When 20 the observer is not directly in the path of the beam, the only point of illumination on such a lamp is the small lens which fits in the reduced light emitting aperture. This lens can be seen from various points of an- 25 gularity forwardly of the lamp. In the present case, I extend a hood out over the light emitting aperture, said hood serving to conceal the lens at all times except when the observer is directly in the path of the 30 beam. Thus, for all practical purposes, I am enabled by the employment of this hood to provide a lamp capable of projecting a suitable beam of great intensity and wherein 35 the source of the light is effectively concealed. In the case of an automobile headlight, the uppermost rays of the cone-shaped beam are kept below a horizontal line, and hence nothing is illuminated but the ground some distance ahead.

40 One form which my invention may assume is exemplified in the following description and illustrated in the accompanying drawing, in which:—

Figure 1 is a central, vertical, longitudinal 45 section through the headlight, or what might be termed a side elevation in section.

Fig. 2 is a front view of the same.

Referring to the drawings in detail, A indicates in general the headlight casing. 50 By referring to the drawings it will be seen that it is oblong and circular in shape, and that it consists of two sections such as shown at 2 and 3, said sections being secured together in any suitable manner by means of 55 the fastening 4. Formed in the forward

portion of the casing section 2 as at 5 is a transparent window or aperture, in which is mounted a condensing lens 6 of the plano-convex type, said lens being secured in a screw cap 7, or any other suitable means to 60 permit it to be readily removed for cleaning or other purposes.

Mounted in the rear portion of the casing is a parabolic reflector 8 and secured in a socket 9 within the reflector is an electric 65 bulb 10 of the usual construction. This bulb is preferably adjustable longitudinally to permit a perfect focusing of the same with relation to the parabolic reflector.

Secured in any suitable manner forward 70 of the parabolic reflector is a condensing lens 11 and interposed between said lens and the opening 5 is a plurality of annular baffle plates 12. These plates are provided with central openings as shown at 13 through 75 which the light rays to be projected pass. The openings 13 in the respective baffles decrease in size as they approach the aperture 5, this being due to the fact that the light rays condensed by the lens 11 assume the 80 form of a cone-shaped beam which has its focal point approximately in the aperture 5. Secured to the cap 7, or, if desired, to the casing 2, is a shield 14. This shield is cone-shaped to conform with the light beam projected through the aperture 5, or the lens 6, and its lower side is preferably cut away as shown at 15.

By referring to Fig. 1 it can readily be seen that if the bulb 10 is properly focussed 90 a beam of substantially parallel rays will be projected against the lens 11 by the parabolic reflector. The rays received by the lens from the reflector when passing through the same are condensed or converged, and are 95 thus brought to a focal point in the aperture 5. They will at the same time spread or diverge after passing through said aperture, and it can, therefore, be seen that a cone-shaped beam is projected, due to the fact 100 that a condensing lens of the plano-convex type is interposed between the parabolic reflector and the transparent aperture. The beam projected through the aperture has the appearance of a cone-shaped beam with 105 the apex of the cone at the aperture, and the aperture through which it is projected is, practically speaking, invisible, due to the fact that the rays are brought to a focal point in the aperture, and also due to the 110

fact that a surrounding shield 14 is employed. It is, therefore, impossible for an observer stationed ahead of the headlight, particularly on either side thereof, to see any 5 visible source of light, except when entering the beam of light projected. This is of great importance when driving an automobile, as the objectionable glare generally produced by headlights is, in this instance, 10 entirely eliminated, due to the fact that no rays are projected above the horizontal line shown at 16. All stray rays caused by imperfections in the reflector 8 or the condensing lens 11 are retained within the head- 15 light, due to the fact that they will either strike the interior surface or the baffle rings 12.

While a specific form of lens is interposed between the transparent aperture and the 20 parabolic reflector 8, I wish it understood that any other form of lens or means capable of the same function, may be employed. Similarly, that the materials and finish of the several parts forming the headlight may 25 be such as the experience and judgment of the manufacturer may dictate.

Important factors to the successful projection of a concealed source of light are (a) employment of a reduced light emitting 30 aperture; (b) projection of a sharply defined cone-shaped beam therethrough; and (c) a hood of about the same divergence as the rays of the beam so that the light rays are not obstructed, such hood being extended 35 far enough ahead to conceal the lens in the light emitting aperture when the observer is out of the direct path of the beam of light. If the hood obstructs the light rays, its interior will thereby be illuminated and also 40 a fringe will be formed around its edge which will be plainly visible to one standing outside of the path of the beam.

Having thus described my invention, what I claim and desire to secure by Letters 45 Patent is:

1. In a lamp, a casing having a reduced light emitting aperture, a source of light in

the casing, means for projecting a cone-shaped beam through the reduced aperture, and a hood on the casing surrounding the 50 light emitting aperture but out of interference with the projected beam, said hood being extended far enough ahead to conceal the light emitting aperture from view when observed from any point not in the direct 55 path of the projected beam.

2. A headlight comprising a casing having a small transparent aperture formed therein, a source of light in the casing, means coöoperating with said light, adapted 60 to project a cone-shaped beam through the transparent aperture, said beam having a focal point in the aperture at which the light rays of the beam cross, a lens in the aperture, a baffle ring within the casing positioned adjacent the focal point of the beam, said ring having a central opening formed therein which is slightly less in diameter than the cone-shaped beam projected therethrough, and a shield exterior of the 70 casing partly surrounding the transparent apertures through which the cone-shaped beam is projected. 65

3. A headlight comprising a casing having a transparent aperture formed therein, 75 a source of light in the casing, a parabolic reflector surrounding said light, means interposed between the reflector and the transparent aperture adapted to concentrate and converge the reflected rays from the parabolic reflector to a common focal point before they are projected through the transparent aperture, and means for rendering the transparent aperture invisible to an observer stationed in front of the headlight, 85 except when standing directly in the beam projected. 80

In testimony whereof I have hereunto set my hand in the presence of two subscribing witnesses.

WILLIAM G. WOOD.
